UNITED STATES PATENT OFFICE.

AUSTIN F. JACKSON, OF TAUNTON, MASSACHUSETTS.

DESIGN FOR A TEA OR COFFEE POT.

SPECIFICATION forming part of Design No. 21,297, dated January 12, 1892.

Application filed December 12, 1891. Serial No. 414,892. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for Tea or Coffee Pots, of which the following is a specification, reference being had to the accompanying drawings, showing a part thereof.

Figure 1 is a side view of a tea-pot constructed in accordance with my design, and Fig. 2 is a plan view.

The leading feature of my design is a series of vertical flutes *a*, running from the base of the pot up to about the middle horizontal line of the body, said flutes terminating in a series of ornamental scallops at their upper edges.

The body of the pot above the flutes curves abruptly inward and is a plain polished surface, from the top of which rises the flared lip *b*. This lip is cut away on each side, and along the edge of the lip and its cut-away portion is an ornamental scroll-work *b* in relief. A central symmetrical double scroll *c* is applied in relief to the center of the cut-away portion of the lip, and on each side of the same there is wrought in relief a floral appendage *d*. The hinged lid is of a flat conical shape, with a fluted canopy *e* applied centrally to the same in relief and surmounted

by a button *f*. The handle has its middle portion *h* smooth, with a polygonal or fluted sleeve *h'* applied to and overlapping the upper portion of the same, and another one *h''* applied to and overlapping the lower portion of the handle. The upper portion of the handle joins the body of the pot at the junction of the lip *b*, and the lower portion of the handle is turned outwardly and joins an offsetting extension *g* from the lower portion of the body. The spout has upon each side two longitudinal creases or indentations *i*, while the outer portion of the spout is overlaid by a fluted sleeve *j*.

What I claim is—

1. The design for a tea or coffee pot, substantially as shown and described.
2. In the design for the tea or coffee pot, as herein shown and described, the lid, as shown.
3. In the design for the tea or coffee pot, as herein shown and described, the handle, as shown.
4. In the design for the tea or coffee pot, as herein shown and described, the spout, as shown.

AUSTIN F. JACKSON.
